ATT'YS.

UNITED STATES PATENT OFFICE

ORVILLE BOYER PETERS, OF WINNIPEG, MANITOBA, CANADA

CONTROLLING DEVICE FOR LOCOMOTIVE OR ENGINE BELLS

Application filed November 5, 1930, Serial No. 493,595, and in Canada September 16, 1930.

This invention relates to controlling device for locomotive or engine bells and an object of the invention is to provide a device whereby a bell of this character may be prevented from revolving and caused to swing in any given arc.

A further object of the invention is to provide a device of this character which will correctly arrest the motion of the bell at a fixed point to prevent it from overturning, without interference with the bell ringer, bell rope or the bell.

A further object of the invention is to provide a device of this character which will allow of a wide range of adjustment of the valve opening in the bell ringer and which will ensure the safe and successful operation of the bell ringer in starting and at all times.

20 A further object of the invention is to provide a device of this character which will tend to lengthen the life of the bell and bell mechanism and which will reduce the cost of maintenance thereof.

25 A still further object is to provide a mechanism of this character which will increase the value of the bell as a warning signal in effecting more prompt, more effective and better regulated operation of the bell.

30 With these and other objects in view the invention consists essentially of a controlling member mounted upon one of the bell trunnions, part of the controlling member being relatively movable to another part thereof and adapted to contact with a suitable stop or the supporting structure of the bell when it has turned to a predetermined position thereby arresting the movement of the bell, 40 as more fully described in the present specification and illustrated in the accompanying drawings which form part of the same.

In the drawings,

Figure 1 is a side elevation of a locomotive bell on its mounting and fitted with the controlling device also shown in elevation.

Figure 2 is an end elevation of the bell on its mounting structure, showing the mounting attachment also in end elevation.

50 Figure 3 is a perspective view of one part

of the control member in the form of a clip or yoke.

Figure 4 is an end elevation of another part of the control member, preferably in the form of an oval collar.

Referring more particularly to the drawings, A indicates the bell support and B indicates the bell oscillatably mounted on the support by means of a cross-arm C provided with trunnions 10 and 11. The trunnion 11 is of greater length than the trunnion 10 so that it projects beyond the support in the extension 12.

Upon the extension 12 a centre piece or collar 13 is mounted which is preferably of oval or substantially oval shape to obtain most effective results. This collar is rigidly secured to the trunnion extension by means of a taper pin 14 so that upon oscillatory movement of the trunnion arm and extension 12 the collar or centre piece 13 will correspondingly move. This collar is made substantially in the form of a drum being provided with peripheral flanges 15 so as to provide a channel 16 therebetween which is based by the drum surface 17 of the collar.

Co-operating with the drum surface of the collar are the inner surfaces of the control member, namely the clips or yokes 18 and 19. The clip or yoke 18 is designed to bear upon the lower drum surface 17 between the flanges 15 and to this end the centre portion of the yoke is bent to form the semi-circular depressed portion 20. The outer ends of this yoke are bent to form the semi-circular downwardly turned projections 21 which extend beyond the ends 22 of the corresponding clip or yoke 19, as will be clearly illustrated in Figure 1.

The co-operating clip or yoke 19 is formed similarly to the yoke 18 with the bent semi-circular portion 23 which is adapted to bear upon the upper drum surface 17 between the flanges 15 in the channel 16 so that the yokes 18 and 19 practically embrace the whole of the drum surface 17 when mounted in normal operating position.

Orifices 24 are provided in the intermediate portions of the yoke 18 which register with corresponding orifices formed in the

ends 22 of the yoke or clip 19 when they are mounted on the collar 13 and through these orifices project suitable bolts 25 upon which is mounted the cross-head 26 extending directly above the collar 13. Coil springs 27 are mounted on the bolts 25 and extend between the ends 22 of the yoke 19 and the cross-head 26 which presses clip or yoke 19 against the drum surface 17 of the collar 13 and similarly through the upward pressure of the springs on the cross-head draws the yoke 18 in bearing engagement with the drum surface 17 through the medium of the retaining nuts 28.

15 The springs 27 may be of any suitable character and may be simple or compound depending upon the relative weight of the bell and the power of the bell ringer, for instance a combination of light and heavy 20 springs of unequal length may be advantageously used. Any alteration in the form of the springs, however, may be made to meet with required conditions.

In operation when the bell is oscillated it 25 will swing until one end 21 of the clip or yoke 18 comes in contact with the bell supporting structure (see Figure 1 as at 29), or any other suitable stop may be provided for this purpose. When contact of this character takes place the swinging movement of the yoke 18 ceases and any further movement of the bell is automatically retarded by the action of the drum surface 17 of the collar 13 in turning and expanding the clips or yokes 35 18 and 19 against the spring tension set up by the coil springs 27 in conjunction with the cross-head 26 and bolts 25. The swinging movement of the bell is therefore arrested in a manner which will not cause a sharp stop of the bell and thereby tend to injure parts but in a manner as to take up any shock upon checking the bell motion.

Due to the fact that the collar 13 and consequently the drum surface 17 thereof is oval 45 in shape, the action of this member upon the yokes 18 and 19 is such as to tend to spread them apart to an increased extent the farther the bell swings. This correspondingly increases the tension of the coil springs 27 50 and increases the material friction between the yokes and the drum surface of the collar 13 so that a natural increased braking action or resistance to motion is the result.

Corresponding action takes place when the 55 bell moves to either side, as will be readily apparent from the foregoing description and the accompanying illustrations.

The length of the arc in which the bell swings may be of course readily controlled 60 and set due to the fact that it is a very simple matter to adjust the controlling device for this purpose. Through increasing or decreasing the tension of the coil springs 27 by tightening or loosening the nuts 28 the pressure of the yokes 18 and 19 upon the col-

lar 13 is increased or decreased as the case may be which correspondingly controls the length of the swing.

Due to the fact that the collar acts upon the bearing surface of the yokes to increasingly resist the movement of the bell after a predetermined point, this collar may be termed an actuator and in the following claims wherever this term appears it will be understood that it refers to the collar 13.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:—

1. A controlling device for bells in combination with a bell oscillatably mounted on a support through trunnions, comprising a control member mounted upon one of the trunnions and adapted to contact with the bell supporting structure at a predetermined point to arrest the motion of the bell.

2. A controlling device for bells in combination with a bell oscillatably mounted on a support through trunnions, comprising a control member mounted upon one of the trunnions and adapted to contact with a stop member at a predetermined point to arrest the motion of the bell, and means in said control member for absorbing the shock of the stopping operation.

3. In a locomotive bell structure means for arresting and retarding the swinging movement of the bell by friction with increasing resistance.

4. In a locomotive bell structure means for adjusting the swing of the bell through a given arc and means for frictionally arresting the motion of the bell with increasing resistance.

5. A controlling device for bells in combination with a bell oscillatably mounted on a support through trunnions, comprising an actuating member mounted on one of the trunnions, a pair of clip members mounted on said actuator, means for retaining said clip members in firm bearing engagement with said actuator, and a stop member adapted to contact with one of said clip members for arresting the motion of the bell at a predetermined point.

6. The device as claimed in claim 5 in which means is provided for absorbing shock in arresting the movement of the bell.

7. The device as claimed in claim 5 in which means is provided for retarding the motion of the bell with increasing resistance.

8. The device as claimed in claim 5 in which the means for retaining the clip mem-

bers in engagement with the actuator comprise coil springs operatively mounted to exert pressure upon both clips.

9. A controlling device for locomotive bells in combination with a bell oscillatably mounted on a support through trunnions, comprising a control member mounted on one of said trunnions, including an actuating member mounted to oscillate with said trunnion, a pair of clip members mounted on said actuator, coil springs for retaining said clip members in firm bearing engagement with said actuator, protruding ends on one of said clip members adapted to contact with a stop member during operation to arrest the motion of the bell, and means on said actuator for retarding further movement of the bell with increasing resistance.

10. The device as claimed in claim 9 in which the actuator is of oval form adapted to increase the frictional engagement between the clips and said actuator in accordance with the movement of the bell.

11. The device as claimed in claim 9 in which the actuator is in the form of a collar member rigidly secured on one of the trunnion shafts formed with a drum surface and peripheral flanges adapted to co-operate with the clip members.

39. In witness whereof I have hereunto set my hand.

ORVILLE BOYER PETERS.
